US00D867110S

(12) **United States Design Patent** (10) **Patent No.:** **US D867,110 S**
(45) **Date of Patent:** **** Nov. 19, 2019**

(54) **CABLE DRUM**

(71) Applicant: **Luceco PLC**, London (GB)
(72) Inventor: **Stephen Gubbins**, Shropshire (GB)
(73) Assignee: **Luceco PLC**, London (GB)
(**) Term: **15 Years**

(21) Appl. No.: **29/614,270**

(22) Filed: **Aug. 17, 2017**

(51) LOC (12) Cl. **08-05**
(52) U.S. Cl.
USPC **D8/359**

(57) **CLAIM**

The ornamental design for a cable drum, as shown and described.

DESCRIPTION

FIG. 1 is a front, right-hand side perspective view of a cable drum embodying my new design;

FIG. 2 is a rear, left-hand side perspective view thereof;

FIG. 3 is a front view thereof;

FIG. 4 is a rear view thereof;

FIG. 5 is a top view thereof;

FIG. 6 is a bottom thereof;

FIG. 7 is a side view thereof as seen from the right-hand side of FIG. 3;

FIG. 8 is a side view thereof as seen from the left-hand side of FIG. 3;

FIG. 9 is a front, right-hand side perspective view similar to FIG. 1, shown with the handle in an open position; and,

FIG. 10 is a front view thereof shown with the handle in an open position.

(Continued)

The broken lines shown in the figures depict portions of the cable drum that form no part of the claimed design.
